UNITED STATES PATENT OFFICE

CARROLL J. SCHUEPBACH, OF KIRKWOOD, MISSOURI, ASSIGNOR TO FREDERICK W. PEETZ, OF ST. LOUIS, MISSOURI

SEWING MACHINE

Application filed December 22, 1928. Serial No. 327,819.

My invention relates to a sewing machine and particularly to one adapted to form pleats in the material operated upon. It is specifically adapted to form pleats in a strip 5 of material forming the neck band of a garment, such as is shown in United States Letters Patent No. 1,603,324 granted to W. J. David on October 19, 1926.

In the accompanying drawings, which 10 illustrate one form of sewing machine made in accordance with my invention, Figure 1 is an end view; Figure 2 is a front elevation of one end of the machine, some of the parts being broken away; Figure 3 is a section 15 taken on the line 3—3 of Figure 1; Figure 4 is a front elevation, on a slightly reduced scale, of the entire machine; Figure 5 is an enlarged section taken on the line 5—5 of Figure 4; Figure 6 is a plan view of a portion 20 of the neck of a garment formed by the machine; and Figure 7 is a section taken on the line 7—7 of Figure 6.

The numeral 8 indicates the head of a sewing machine of usual construction mounted 25 on a work table 9 and provided with a presser foot 10 and a needle bar 11 carrying two needles so as to simultaneously form two parallel rows of stitches. 12 is the main shaft of the machine driven from any suitable 30 source of power and operating the needle bar, shuttles, or loopers and other usual moving parts through mechanism not shown as it may be of any well known construction.

Secured to the work table 9 in alignment 35 with the presser foot is a trough-shaped guide 13 for delivering under the presser foot a strip of tape 14 wound on a reel 15 carried in brackets 16 on the under side of the work table. A roller 17 may be secured 40 to the edge of the work table to prevent friction of the tape thereon.

Situated directly above the guide 13 is a second trough-shaped guide 18 for delivering under the presser foot a second strip of 45 tape 19. This tape 19 is wound on a reel 20 mounted on an arm 21 carried on a plate 22 secured to the end face of the sewing machine head. This plate also carries a bracket 23 supporting the guide 18 which is 50 inclined so as to provide ample room at the

forward end for the insertion of the garment 24 while at the rear end it is almost in contact with the guide 13. The tape 19 as it enters the guide 18 is threaded around pins 55 25, as best shown in Figure 5. These pins act as a brake or retarding device to prevent surplus tape being drawn into the guide by the rapid motion of the pleating blade.

A thin strip of spring material, preferably 60 steel, forms the pleating blade 26, the lower end of which enters the guide 18 and the upper end of which is secured in a stud 27 carried by a lever 28 pivoted at 29 to the plate 22. A connecting rod 30 extends from the upper end of the lever 28 to a wrist pin 31 65 slidingly mounted in T-slot 32 in a disk 33. The position of the wrist pin in the slot may be adjusted by means of a screw 34 to vary the length of the stroke of the pleating blade. A short shaft 35 journaled in the plate 22 70 carries the disk and a gear wheel 36 meshing with a gear wheel 37 on a shaft 38 extending to the opposite end of the machine head and connected through a train of gearing 39 with the driving shaft 12 of the machine. This 75 train of gearing is so proportioned that it, together with the wheels 36 and 37, will make the necessary reduction in speed so that, for example, the pleating blade will vibrate once to each ten strokes of the needle bar. The 80 train of gearing is enclosed in a gear casing 40 mounted on the machine head, and has interposed in it a clutch 41 or equivalent means for throwing the shaft 38 into and out of engagement with the shaft 12. A finger lever 85 42 controls the action of the clutch.

The operation of my machine is as follows: The two tapes 14 and 19 are passed through the guides 13 and 18, respectively, and positioned under the presser foot. The material 90 24 of the garment may now be fed between the two layers of tape, as shown in Figure 5, and stitched together as shown at the left hand end of Figure 7. When the point in the work is reached where it is desired to 95 form hook engaging pockets, the lever 42 is moved to throw the shaft 38 into operative engagement with the shaft 12 when the pleating blade will be vibrated to fold the upper tape 19 into pleats which are firmly secured 100.

to the material 24 by the rows of parallel stitches 43. As soon as the desired number of pleats are formed the lever 42 is moved in reverse direction to render the pleating mechanism inoperative and the work finished. The operation of forming the neck band is thus continuous as it is unnecessary to stop the machine when the pleating device is thrown into or out of operation. The width 10 of the pleats may be varied as desired by turning the screw 34 to move the wrist pin 31 toward or away from the center of the disk 33, thus changing the length of stroke of the pleating blade.

15 While my machine is particularly designed for forming hook engaging pockets in the neck bands of garments, such as described in the David patent above referred to, it may be used for other purposes where it is desired 20 to form pleats in a tape or similar narrow strip of material.

Having fully described my invention, what I claim as new and desire to secure by Letters Patent of the United States is:

25 1. In a device of the class described, the combination with a sewing machine head including a presser foot and needle bar, of a supporting member secured to said head, a tape guide carried by said supporting member and terminating adjacent to said presser foot, a lever pivoted to the supporting member, a pleating blade on said lever and co-operating with said guide, a shaft mounted in said supporting member, an adjustable wrist 30 pin carried by said shaft, connections between said wrist pin and lever, connections from said shaft to the needle bar actuating mechanism, and clutch mechanism interposed in said latter named connections.

40 2. In a device of the class described, the combination with a sewing machine head including a presser foot and needle bar, of a supporting member secured to said head, a tape guide carried by said supporting member and terminating adjacent to said presser foot, a lever pivoted to the supporting member, a pleating blade on said lever and co-operating with said guide, a shaft mounted in said supporting member, an adjustable 45 wrist pin carried by said shaft, connections between said wrist pin and lever, a gear wheel on said shaft, a second shaft extending to the rear of the machine and provided with a gear wheel meshing with said first named 50 gear wheel, reduction gearing between said second named shaft and the needle bar actuating mechanism, and a clutch interposed in said reduction gearing.

In testimony whereof, I hereunto affix my 60 signature, this 20th day of December, 1928.

CARROLL J. SCHUEPBACH.
